UNITED STATES PATENT OFFICE.

OSCAR R. LOOKER, OF DETROIT, MICHIGAN.

DESIGN FOR A PEN-RACK.

SPECIFICATION forming part of Design No. 33,727, dated December 18, 1900.

Application filed November 22, 1900. Serial No. 37,403. Term of patent 7 years.

To all whom it may concern:

Be it known that I, OSCAR R. LOOKER, a citizen of the United States, residing at Detroit, in the county of Wayne, State of Michigan, have invented and produced a new and original Design for a Pen-Rack, of which the following is a specification, reference being had to the accompanying drawings, and to the letters of reference marked thereon, which form a part of this specification.

This invention relates to a design for a pen-rack; and it consists in the configuration illustrated in the accompanying drawings, in which—

15 Figure 1 is a perspective view of my design for a pen-rack. Fig. 2 is a central longitudinal section therethrough.

The main feature of the design consists in a rectangular tray-like receptacle having a bottom mounted upon supporting-legs and also having vertical ends and sides. The side which forms the back of the tray stands higher than the front side and is inclined. One of the ends stands higher than the other, and 25 its upper edge is convoluted. Crossing the tray transversely between its ends is a partition, whose upper edge is also convoluted to

correspond with said end. The front side of the tray extends from one end to said partition only.

Referring to the characters of reference, 1 designates the bottom of the tray or rack, and 2 the legs upon which it is supported. The back side of the tray is indicated at 3 and the front side at 4. The high end of the tray is 35 indicated at 5, whose upper edge is provided with the convolutions 6. 7 designates the opposite end of the tray; 8, the transverse partition having the convolutions 9 therein. At one end of the tray is a ledge 10, raised above 40 the bottom thereof, the whole presenting a harmonious and ornate figure.

Having thus fully set forth my invention, what I claim as new, and desire to secure by Letters Patent, is—

The design for a pen-rack, substantially as herein shown and described.

In testimony whereof I sign this specification in the presence of two witnesses.

OSCAR R. LOOKER.
